PATCH APPLYING AND LAMINATING MECHANISM FOR PAPER WORKING MACHINES

Edwin G. Staude, Minneapolis, Minn.

Application April 1, 1940, Serial No. 327,144

36 Claims. (Cl. 93—61)

This invention relates to improvements in patch applying machines; that is, machines for applying patches, linings, or covers to sheet material. Machines of this character are adapted to apply a patch coextensive in length with the material to be patched, but the primary and distinctive utility of a patch applying machine resides in the fact that it is adapted to apply patches which are shorter than the patched articles, in exact registration with predetermined areas thereof.

A machine of the character referred to includes basically mechanism for feeding a first material to be patched, a patch applied adapted to roll patches progressively into contact with spaced areas of the first material, mechanism for paying out a web of patch material to the patch applier at a slower speed than the surface speed of the patch applier, means for severing successive patches from the leading end of the web, and means for causing the patch applier to exert a slip drag on the web before severing, and to advance the severed path to meeting relation with the first material without slipping, all as broadly disclosed in my Patent #1,969,106 of August 7, 1934. The modern trend has been toward the use of suction for causing the patch applier to exert a slip drag on the web before severing and to advance the severed patch to meeting relation with the first material without slipping; also to the use of a rotary cutter cooperative with the patch applier for effecting severance of the patches.

The use of suction has certain disadvantages. A vacuum system is expensive to install and operate. It is inherently limited in speed of operation. The suction ducts become clogged with lint and dirt which always accumulates around any paper working machine. Frequent and tedious cleaning is necessary, and in the intervals between cleanings the suction gradually becomes less effective and more sluggish and uncertain in its action.

Then too, in order to make the suction operated machines practical, the air current is caused to be quickly reversed to blow the patch from the surface of the patch applier at the time of contact with the adhesive on the moving blank to which the patch is to be applied. A serious disadvantage of this scheme resides in the fact that in blowing off it is a very difficult matter, at some time or other, to prevent oil from working through the oil filter and the passages from the vacuum pump and coating the surface of the cylinder. This, of course, soils the product and

in time interferes with the operation of the machine.

It is an important object of the present invention to provide improved auxiliary feeding means cooperative with the patch applier and bearing lightly thereagainst for causing the patch applier to exert a slip drag on the leading end of the web before cutting and to carry the cut patch forward without slipping.

In accordance with a practical and advantageous embodiment of the invention, and as disclosed herein, the auxiliary feeding means desirably takes the form of friction belt devices which are individually adjustable laterally of the path of web feeding, and which are positively driven in unison with the surface speed of the patch applier. These belt devices form continuous guides for the web and serve also to exert an uninterrupted smoothing tension upon the leading end of the web before the patch is cut.

The fact that the belt devices are positively driven is an important feature of the invention because maintenance of the speed of the belts and their pulleys at the surface speed of the patch applier does not depend upon contact of the belts with the patch applier. In the case of long patches particularly there is never any need to accelerate the belt mechanism through the web or the cut patch, so that the only inertia to be overcome is that of the light patch material itself.

The use of belt devices is also important because the pressure of a belt throughout its entire active stretch can be adjusted by the single and simple operation of adjusting the tension of the belt. It is a further important feature of the invention, therefore, that the auxiliary feeder comprises belt devices, together with means for adjusting the tension of the belts to produce any desired pressure of the belts against the patch applier.

It is a further feature that the opposite ends of the active or patch applier engaging stretches of the belts are guided by rollers which are so mounted that the driving tension causes the rollers to be drawn lightly toward the belt applier. These guide rollers are so arranged that the pull upon each roller is in a line which passes near to the pivot of the roller support, but between the pivot and the patch applier.

I have found that in order to use longitudinal anvil bars on the periphery of a patch applying cylinder it is necessary to provide sections of sheet rubber thereon between the anvil bars.

Vulcanization of rubber to the cylinder is a dif-

ficult and expensive operation. There is also a serious objection to this procedure, because if the rubber surface is injured or becomes worn, the entire cylinder must be removed from the machine and new rubber vulcanized thereon to replace the worn or injured surface.

In order to obviate this serious objection, I have invented a very simple manner of replacing or renewing the rubber surface between the anvil bars, against which the continuously revolving knife acts. I accomplish this by covering the cylinder between the anvils with sections of curved sheet metal plate to which sheet rubber has previously been vulcanized. I secure these sections in position by any practical method, such as suitable screws, but preferably by beveling the edges of each section and clamping it in position on the cylinder by suitable clamping means held in place by easily accessible cap screws.

I can purchase these rubber covered sheets, which are laminated to type metal, in large flat sheets, commercially, and my method is to cut this material to proper shape and size and to curve it to fit same on the cylinder. Such material serves as a friction surface of high wearing quality. With this construction I provide a comparatively inexpensive, easily replaceable for repair, rubber surface on the patch applying drum. I have devised also a very practical means for holding such rubber faced sections in place by the anvil bars. The anvil bars can be quickly removed in the event that the sections are damaged or worn. The whole patch applying cylinder is therefore readily adaptable for quick repairs when required.

Further important features of the invention have to do with the provision of improved means for quickly altering the machine so that one, two or three patches may be cut and applied for each revolution of the patch applying and cutting cylinder. The rotary cutter which cooperates with the patch applying and cutting cylinder is arranged to receive one, two or three knives simultaneously, the knives being uniformly spaced whenever a plurality of them is used. Readjustment can be made in some instances, as when changing from three cuts per revolution to one cut per revolution, simply by removing two of the knives, but in other instances it is necessary to replace anvil bars of the patch applying and cutting cylinder by non-cutting bars which perform the clamping function of the anvil bars, but which are formed with grooves to permit the knives to pass without cutting. Provision is made for facilitating the rapid interchange of anvil bars and non-cutting bars.

There are also certain zones of the patch applying and cutting cylinder which would normally be engaged by certain of the knives, but upon which no cutting is ever performed. These zones are grooved to permit the knives to pass without cutting and without marring the patch web material.

Although the web is normally paid out to the patch applying and cutting cylinder at a lesser speed than the surface speed of the cylinder, it is jerked forward at the speed of the cylinder during the period when it is clamped to the cylinder by a knife and before the cutting is completed. A compensator is provided for forming a loop in the supply web between the cutting intervals and for causing the loop material to be yielded to the cylinder as the web is jerked forward.

A feature of the invention has to do with the

provision of adjustable cam means for causing the compensator to perform its operating cycle one, two or three times in each revolution of the patch applying and cutting cylinder in accordance with the number of cutting operations for which the machine is set and in timed relation to such cutting operations.

I have found that whether I use vacuum or not, it is difficult to hold the web against the surface of the cylinder or patch applying member immediately after a sheet has been severed.

Where I use vacuum to hold the web against the cylinder, I find that the web drops off whenever the machine is stopped a few seconds and the vacuum disappears. I have solved the problem by the addition of small rollers which are preferably idler rolls and which press the web of cellulosic material against the cylinder at all times before and after severing so rethreading of web on starting is eliminated. It is broadly new to use any form of mechanical means for the purpose stated. I therefore consider these idler rolls an important improvement.

As I use no suction to hold the sheet to the cellulose applying drum, I have found that the ordinary "tack" in the cellulose adhesive is sufficient to pull the cellulose sheet away from the rubber covered drum without the need of an air blast or reversed suction to quickly force the sheet off from the cylinder. This is particularly true when I provide grooves in the cylinder, as shown in Figure 12, which prevent "suction" attraction and reduce the area for "static" action.

I consider my invention a very important improvement over present machines of this type, particularly in its simplicity and inexpensive upkeep.

The objects, features and advantages of this invention will be more completely set forth in the description and drawings forming a part of this application.

In the drawings—

Figure 1 is a vertical sectional view of the part of a machine which embodies my invention.

Figure 2 is a horizontal section taken substantially on the line 2—2 of Figure 1.

Figure 3 is a vertical section taken substantially on the line 3—3 of Figure 1.

Figure 4 is a plan view of the lower portion of the mechanism shown in Figure 1, and shows a carton blank passing from the conveyor chains over a pressure roll to the delivery belt.

Figure 5 is an enlarged detail sectional view showing a knife edge of the cutting roll in contact with an anvil bar of the laminating cylinder, and also shows how the knife blade is adjustably secured in said cutting roll.

Figure 6 and 6a is a detail view showing an anvil bar removed from its groove and a section of the laminating cylinder showing the groove.

Figure 7 is a longitudinal sectional view of a part of the laminating cylinder, showing the manner of clamping the anvil bars in position therein.

Figure 8 is a side view of the changeable cam device which is mounted on one end of the laminating cylinder shaft.

Figure 9 is a detail view of the detachable clamp lug which allows the removal of an anvil bar without disturbing other parts of the laminating cylinder.

Figure 10 is an end view of a non-cutting bar which is adapted to replace a regular anvil bar under certain conditions.

Figure 11 is a diagrammatic view illustrating

the manner of arranging the film cutting bars for various sizes of carton blanks.

Figure 12 shows how the rubber surface of the laminating cylinder may be provided with circumferential grooves, and

Figures 13, 14, 15 and 16 are enlarged views of the friction tape mechanism, which illustrate more clearly the construction and important functions of same.

The mechanism shown in the drawings is only a part of a machine for applying a cellulosic material patch over openings in envelopes and paper cartons, as the complete machine includes means for feeding the blanks and carrying them along beneath an adhesive applying unit to the herein described cellulosic material applying mechanism, from which said blanks are then projected into a stacking unit, in a manner quite similar to that shown in the Patent #1,969,106 before referred to, but, as my present invention only pertains to the cellulosic material applying unit of the machine, I have only shown the improved mechanism for that purpose, with portions of the frame members A—A, conveyor chains B—B, and stacking belt C of said machine.

In the several views, numeral 3 indicates a substantial shaft which extends across the machine and is journaled in bearings 4 and 5 in the frame members A—A, and a third bearing 6 is provided for said shaft in a bracket 7 which extends inwardly from the right-hand frame member A, above an extremely wide carton blank path, to provide additional support for the shaft 3. This shaft is continuously rotated in said bearings by a gear 8 which is secured at the outer end of said shaft and driven by another gear (not shown) which is a part of the machine drive transmission.

Another substantial shaft 9 is mounted in vertically adjustable bearings 10, 11 and 12 directly above the shaft 3, and a gear 13 is adjustably secured to the outer end of this shaft in position to mesh with the driven gear 8. The shaft 9 has an integral cylindrical portion 14 of enlarged diameter in which longitudinal grooves 15 are provided, and a knife blade 16 has a bevelled cutting edge 17 projecting beyond the periphery of the cylinder 14 and is adjustably secured in the groove 15 between bars 18 and 19 which are clamped therein by a series of headless set screws 20. The bars 18 are divided into sections which each have a number of adjusting screws 21 passing therethrough into contact with the bottom of the grooves 15, and said sections each have a flange 22 on which the inner edge of the knife blade 16 rests, so that when the set screws 20 are loosened, the knife blade may be forced outwardly by the screws 21 to a desired point where said knife is then secured in position by tightening the screws 20 against the locking bar 19. I prefer to provide three of the grooves 15, which are spaced an equal distance apart in the periphery of the cylinder 14, although in some cases a greater or less number of grooves may be preferred.

The cutting edge 17 of the knife blade 16 is adapted to contact the smooth, hardened outer surface of a number of anvil bars 23 which are inserted in longitudinal grooves 24 in the periphery of a cylindrical drum 25 which is secured on the shaft 3 immediately below the knife carrying cylinder 14. The diameter of the cylinder 25 is practical twice the diameter of the cylinder 14, and as the gear 8 is exactly twice

the diameter of the gear 13, the gear 13 may be adjusted so that the knife edges 17 will always contact a certain point near the center line of the anvil bars at every revolution of the cylinder 25. I have arranged four anvil bars at points exactly 120°, 60°, 60° and 120° apart on the periphery of the cylinder 25, for the purpose hereinafter described, and for the purpose of securing the anvil bars in place in their respective grooves, I provide a removable lug 26 at each end of said bars so that an inwardly projecting lip 27 on such lug will engage a bevelled end of an anvil bar to force same into snug position in a groove 24 when a screw 28 is turned to draw the lug into the position shown in Figure 7. The screws 28 pass through holes 29 in the lugs into threaded holes in discs 30 which are secured to the ends of the cylinder 25 by cap screws 31. An inwardly extending flange 32, at the outer edge of said discs, is bevelled to correspond with the lip 27, for the following described purpose. As an important feature of my invention consists of using a resilient material having a certain degree of dry surface adhesion, such as vulcanized sheet rubber, and as it is impractical and too expensive to vulcanize sheet rubber directly to the surface of the cylinder, I conceived the idea of using a commercially manufactured product which consists of a special sheet metal to which a sheet of high-grade rubber is vulcanized so as to make the two materials almost inseparable. A section of this laminated material is curved to fit the periphery of the cylinder 25, between each two adjacent anvil bars, and the rubber part 33 of same is cut away at its longitudinal edges to expose the edge portion of its sheet metal part 34, which edge is then disposed in under the flanges 23 of the anvil bars to be securely held in place thereby when said anvil bars are clamped into fixed position. The ends of these rubber cover sections are then bevelled to fit snugly beneath the bevelled flanges 32 of the discs 30 so as to be held firmly in position on the cylinder.

This method of providing a rubber coated surface for the cylinder 25 makes it an easy matter to remove and replace any or all sections which may become damaged or worn, at comparatively low cost.

Stationary shafts 35 and 35' form cross-bars between the frame members A—A, and a pair of spaced castings 36 are adjustably clamped thereon by hinged dogs 37 having set screws 38. The castings 36 have bearings for rolls 39 and 40 over which a comparatively wide belt 41 is continuously driven through gears 42 and 43, and a series of idler rolls 44 are also journaled in the castings 36 to support the upper horizontal stretch of the belt 41. Arms 45 are pivoted on the castings 36 and have bearings at one end for a driven shaft 46 on which a roll 47 is mounted and adapted to be forced upwardly toward the cylinder 25 by compression springs 48 which are carried in the projecting end 36' of the castings 36. The roll 47 is driven by a gear 46' with a uniform peripheral speed identical to that of the cylinder 25, and cooperates with said cylinder in feeding the carton blank 49 from the conveyor chains B—B to the belt 41 while the Cellophane patch is being attached to said carton. It is occasionally necessary to move the roll 47 away from the cylinder 25, and I therefore provide small eccentric cams 50 on a shaft 51, directly beneath the rear end of the arms 45, by which the roll 47 may be forced

away from the cylinder 25 when the cam shaft 51 is turned by a handle 52. Screws 53 are provided in the rear end of the arms 45 to contact the cams 50 and provide for adjustment of the required space between the roll 47 and cylinder 25.

Another pair of stationary shafts 54 and 55 form cross-bars between the frame members A—A, above the cross-bars 35 and 35', and a pair of spaced castings 56 and 57 are mounted on said cross-bars and have fixed bearings 58 and 59 for a driven shaft 60 on which a rubber roll 61 is mounted, while an adjacent rubber roll 62 is mounted on a parallel shaft 63 which extends through slidable bearings 64 and 65, and is oppositely driven from the shaft 60 by gears 66 and 67. Cams 68, similar to the cams 50, are mounted on a cam shaft 69 which is rotatably carried by the bearings 64 and 65, and adjusting screws 70, located in the castings 56 and 57, contact the cams 68 to force the rubber rolls 61 and 62 together to a point determined by adjustment of the screws 70 on the high point of the cams 68. A handle 71 on one end of the cam shaft 69 allows turning said shaft and the cams thereon to a point where the compression springs 72, which are disposed between the bearings 58—64 and 59—65, forces the rubber rolls apart when so desired. The rubber rolls 61 and 62 are driven by a variable speed transmission device (not shown) which is adjustable to enable any desired length of web, within the capacity of the machine, to be paid out during one revolution of the shaft 3. The rolls 61 and 62 are driven through a chain 73 and gears 74, which gears are splined on the shaft 60.

Any suitable means may be used for supporting a roll of cellulosic material, or other kind of thin pliable material, such as glassine, etc., of desired width, above the rubber rolls 61 and 62, but I prefer to use the means shown in Figure 1, whereby the roll of thin material 75 is supported on a shaft 76 which is detachably held in the rear end of arms 77 which in turn are adjustably secured on a shaft 78 having bearings in upright extensions 79 on the castings 56. A depending arm 80 is fastened to one end of the shaft 78, and the lower end of this arm is connected to a helical spring 81, on the extension 79, by a threaded rod 82 and a hand-wheel 83, whereby the weight of the roll 75 may be counterbalanced. The material from the roll 75 is passed downwardly between the rubber feed rolls 61 and 62, over an idler roll 84, and under a loop-forming roll 85, to the cylinder 25, (see Figure 1). Small wheels 86 are carried by arms 87 which are hinged on a fixed shaft 88 so as to allow said wheels to rest by gravity on the material 75 at a point preceding the cut-off point, to hold said material against the cylinder surface 33 with just sufficient pressure to allow the material to slip on said surface up to the point of cut-off, which takes place when the bevelled edge 17 of the knife 16 strikes the anvil 23. At this point the material, while momentarily contacting the anvil 23 must instantly travel at the surface speed of the cylinder 25. In order to allow this momentarily increased speed of web feed I provide the loop-forming roll 85 which is caused to rise instantly in time with the cut-off mechanism and thus yield up loop material momentarily during the cut-off operation, after which the roll 85 will slowly swing downwardly again to reestablish the loop in the cellulosic

material in preparation for the next cut-off period.

The roll 85 rotates freely in arms 89 which are secured on a shaft 90, and said shaft is adapted to be oscillated by an arm 91 carrying a roller 92 in contact with a cam device 93 which is secured to the end of the shaft 3, and said cam device has a series of projections 94 thereon which are spaced to cause the shaft 90 to be oscillated so as to swing the roll 85 up and down in timed relation with the material cutting-off operation. The cam device 93 is composed of three discs having identically shaped projections 94, and said discs are provided with a series of holes for dowel pins 95 and cap screws 96 which are so arranged that said discs may be shifted around on their common axis to make either a one-point, a two-point or a three-point cam as desired, and a compression spring 97 is adapted to engage the arm 91 to force the roller 92 against the periphery of the cam discs so as to impart a controlled oscillating movement to the shaft 90.

A revolving brush 98 is disposed in bearing blocks 99 at the lower end of the castings 56, and is driven by a shaft 100 which is provided with universal joints 101 and a gear 102 which is in driving contact with the gear 8 through an intermediate pinion gear, (not shown), and said brush is adapted to sweep the surface of the cylinder 25 to prevent accumulation of foreign matter thereon. A sheet metal guard 103 is placed immediately above the brush 98 to prevent the nearby thin cellulosic material from being damaged by said brush.

For the purpose of holding the severed portion of cellulosic material in light contact with the rubber covered surface of the rotating cylinder 25, I prefer to locate a shaft 104 in parallel relation with the forward side of said cylinder. One end of said shaft has a bearing in one frame member A while the other end has a notch to engage a pin 105 in a sleeve 106 which is secured to an extension shaft 104' having a bearing in the other frame member A. A collar 106' holds the shaft 104 in place, but allows easy removal thereof when desired, and a gear 107 is secured to the outer end of the extension shaft 104' and is driven through an intermediate gear 107' by a ring gear 108 which is mounted on the inside of the gear 8. A pulley 109 has a key 110 which is slidable in a keyway 111 in the shaft 104, and a flange 109' on said pulley hub is adapted to hold the pulley in place adjacent a metal plate 112 through which said shaft extends. The upper edge of the plate 112 is fastened to a yoke 113 which is adjustably secured to a cross-bar 114, and rearwardly extending arms 115 and 116 are pivotally mounted at the upper and lower edge, respectively, on said plate. Small pulleys 115' and 116' are journaled near the rear end of the arms 115 and 116, and a small pulley 119 is journaled on a stationary stud immediately above the pulley 109 while a similar small pulley 119' is journaled on a stud 120 which is adjustably secured in a slot 121 in the front edge of the plate 112. An endless tape belt 122 extends around the driven pulley 109 and over the four small idler pulleys into contact with the forwardly curved surface of the cylinder 25, between the pulleys 115' and 116', and this belt is preferably made of smooth, non-elastic flexible fabric, such as an endlessly woven silk or linen ribbon.

I prefer to use two of these belt units which may be adjusted separately to suitable positions

on the cross-bar 114. By adjustment of the stud 120 the belts may be tensioned independently to contact the cylinder surface with just sufficient pressure to permit the leading end of the web of cellulosic material to slip before severance, but to cause the severed sheet of cellulosic material to be moved along at a speed identical with that of both cylinder surface and belt after severance. As indicated by the large arrows in Figure 13, an upward adjustment of the stud 120 will cause the arms 115 and 116 to be drawn towards the surface of the cylinder, and will also serve to increase the contact pressure of the belt 122 thereon. The swinging movement of the arms 115 and 116 is limited by pins 123 thereon which project into slots 124 in the plate 112.

In Figure 12, I have shown how a series of shallow, circumferential grooves 125 may be provided in the rubber surface of the cylinder, between the anvil bars, for the purpose of allowing air to enter between the cylinder surface and the cellulosic sheet, in order to facilitate the pulling of said sheet from said surface.

In Figure 10, I show a non-cutting bar 117 having a longitudinal groove 118 in its exposed surface which prevents the knife edge 17 from cutting the passing material at that point, and similar grooves are provided in the rubber covered sections at points X—X (see Figure 1) for that same purpose, as will hereinafter be described. Non-cutting bars 117 may be substituted for the anvil bars 23 as required.

To adapt the machine for cartons of various lengths, within certain limits, and in order to obtain correspondingly increased capacity with the shorter carton blanks, I have spaced the grooves for the cutting knives and anvil bars in their respective cylinders so that by arranging three different combinations of knives and anvils in said grooves, I can double or triple the short blank capacity of the machine without increasing the R. P. M. of same.

With the first combination, and conveyor chains having feed lugs 30 inches apart, blanks from 13 inches to 27 inches may be handled by providing a cutting knife in groove c (see Figure 11), an anvil bar in groove d, a non-cutting bar 117 in groove f and no knives in grooves a and b; while a single point is used on cam 93; or by providing non-cutting bars 117 in grooves e, f and g even though knives are present in grooves a, b and c.

With the second combination, and conveyor chains having feed lugs 15 inches apart, blanks from 8 inches to 13 inches may be handled by providing a knife in groove c only, with anvil bars in at least grooves d and f, or by providing non-cutting bars in grooves e and g, with knives in grooves a, b and c. Two points of the cam 93 are used.

I have described what I believe to be the best embodiments of my invention. I do not wish, however, to be confined to the embodiments shown, but what I desire to cover by Letters Patent is set forth in the appended claims.

I claim as my invention:

1. In a machine of the class described, means by which blanks are consecutively fed, means for applying severed lengths of thin material to blanks on said first feeding means, means for feeding material to the applying means, means for severing the material while on said applying means, mechanical means contacting and yieldably pressing the material against the applying means as it approaches the severing means, driv-

en means yieldably pressing the material against said applying means after it has passed the severing means, and means adapting the material which is approaching the severing means to travel at the same surface speed as that of the applying means, during severing.

2. A device of the class described comprising, a feeding cylinder, means for feeding blanks so as to receive material fed from the cylinder, means for cutting the material while on the cylinder, a supply of material and means by which the material is fed to the cylinder for cutting, including first means yieldably pressing the material against the cylinder as said material approaches cutting position, means synchronized with the cutting means for slackening the material during cutting, and second means yieldably pressing the material against the cylinder before and after cutting and after it has passed cutting position and adapted to allow slippage of the material before cutting and to positively feed the material after cutting, said second means being driven at the same speed as that of the cylinder.

3. In a machine of the class described, comprising a rotating cylinder having longitudinal anvil bars removably secured in grooves in its circumferential surface, a timed rotating cutting roll coacting with said cylinder and provided with projecting longitudinal knife edges adapted to contact said anvil bars, sections of suitable friction material removably secured to the surface of said cylinder between said anvil bars, and a shallow longitudinal groove provided in some of said anvil bars and friction material to prevent contact of said knife edges therewith when no cutting action is desired at said contact point.

4. In a machine of the class described, having means for feeding a first material into contact with a rotating cylinder, a hardened surface on said rotating cylinder, a cutting cylinder located adjacent and cooperating with said rotating cylinder, cutting knives in said cutting cylinder adapted to cut against said hardened surface on said rotating cylinder, means for feeding a second material from a roll between said cutting cylinder and said rotating cylinder for severing said second material into predetermined lengths, rollers for holding said second material into contact with said rotating cylinder before severing and adapted to hold the unsevered second material against the rotating cylinder immediately after severing to cause continuous forward feeding of said second material, and means for holding said severed second material into contact with said rotating cylinder after severing to deliver said second material into contact with said first material.

5. A machine of the class described having timed feeding means for feeding spaced adhesive coated blanks, and continuously operating feeding means for feeding a web of thin cellulosic material, comprising a rotating cylinder against which said thin cellulosic material is fed, longitudinal anvil bars located in the surface of said rotating cylinder, a rotating cutting roll for cutting off predetermined lengths of thin cellulosic material coacting with said cylinder, said cutting roll being provided with projecting longitudinal cutting knives contacting said anvil bars in said rotating cylinder, sections of removable friction material secured between said anvil bars on said rotating cylinder, means for holding said thin cellulosic material in light contact with said sections of friction material, said last means and

said friction material being adapted to feed said thin cellulosic material forward in taut condition before severing through slippage by moving faster than said cellulosic material and positively feed same after severing into contact with said adhesive coated blanks.

6. A paper fabricating machine having means for feeding spaced blanks past a rotating cylinder, means for yieldingly pressing said passing blanks against said cylinder, a parallel cutting roll spaced slightly from said cylinder and rotated at identical surface speed, projecting knife edges on said cutting roll adapted to contact cooperating cutting means on the periphery of said cylinder, adjacent feed rolls adapted to project a patching material at a speed which is considerably slower than the surface speed of said cylinder, means for directing said patching material into the space between said cutting roll and said cylinder and means for periodically creating a slack in said material between said feed rolls and said space, means for pressing said slow moving patching material into light frictional contact with the faster moving cylinder surface before entering said space, and auxiliary forwarding means traveling at cylinder surface speed for holding said patching material in light frictional contact with said cylinder after passing said space.

7. A machine of the class described having timed feeding means for feeding spaced adhesive coated blanks, means for feeding and delivering a thin pliable cellulosic material from a web to a rotating cylinder, means cooperating with said rotating cylinder for severing a sheet from the end of said web, means for holding said sheet into contact with said rotating cylinder, said means comprising endless belts passing from a driven pulley on an adjacent shaft to small idler pulleys mounted on the outer ends of hinged arms which diverge to allow said belts to engage the downwardly moving surface of said rotating cylinder, an adjustable belt tightening device arranged to independently increase or decrease the tension of said belts while simultaneously drawing said diverging arms toward said cylinder to press said idler pulleys proportionately against said surface with any desired contact pressure for the purpose described.

8. In a machine of the class described, means by which blanks are consecutively fed, means for applying severed lengths of thin material to blanks on said first feeding means, means for feeding material to the applying means, means for severing the material while on said applying means, a pair of rollers contacting and yieldably pressing the material against the applying means as it approaches the severing means, a pair of means yieldably pressing the material against said applying means after it has passed the severing means and driven at the same surface speed as that of the applying means and acting before severing to allow slippage of the material on the drum, and after severing to positively advance the material.

9. In a machine having means for feeding an article, a drum for advancing severed lengths of thin, pliable material for registration with and application to a fed article, a rotary knife cooperating with said drum to sever the material while on the drum, means for feeding the material to the drum, means yieldably pressing the material against the drum as it approaches the severing point to hold the material taut, a belt positively driven in synchronism with the drum and pressing the material against the drum at a point

beyond the severing point to permit continuous slipping between the material and the drum before severing and to positively advance the material after severing, and means positively synchronized with the rotating knife and drum for causing the material approaching the drum to instantly travel at the same surface speed as the drum, as severing occurs.

10. In a patch applying machine, in combination, means for feeding a first material to be patched, a patch applier for rolling patches progressively into contact with the first material, means for driving the patch applier in unison with the first material feeding means, means for supplying a web of patch material to the patch applier at a slower speed than the surface speed of the patch applier, means for cutting patches of predetermined length from the leading end of the patch web, auxiliary feeding means bearing lightly and with yielding force against the patch applier for cooperating with the patch applier to exert a slip drag on the leading end of the patch web as the web is being supplied to the patch applier before severance and to carry the patch forward without slipping for application to the first material after severance, and means for positively driving the auxiliary feeding means in unison with the surface speed of the patch applier.

11. In a patch applying machine, in combination, means for feeding at constant speed a first material to be patched, a patch applier for rolling patches progressively into contact with the first material, means for driving the patch applier in unison with the first material feeding means, means for supplying a web of patch material to the patch applier at a slower speed than the surface speed of the patch applier, means for cutting patches of predetermined length from the leading end of the patch web, auxiliary feeding means bearing lightly and with yielding force against the patch applier for cooperating with the patch applier to exert a slip drag on the leading end of the patch web as the web is being supplied to the patch applier before severance and to carry the patch forward without slipping for application to the first material after severance, and means for positively driving the auxiliary feeding means in unison with the surface speed of the patch applier.

12. In a patch applying machine, in combination, means for feeding a first material to be patched, a patch applier for rolling patches progressively into contact with the first material, means for driving the patch applier in unison with the first material feeding means, means for supplying a web of patch material to the patch applier at a slower speed than the surface speed of the patch applier, means for cutting patches of predetermined length from the leading end of the patch web, belt means bearing lightly against the patch applier over an extensive arc thereof for cooperating with the patch applier to exert a slip drag on the leading end of the patch web before severance and to carry the patch forward without slipping for application to the first material after severance, and means for positively driving said belt means in unison with the surface speed of the patch applier.

13. In a patch applying machine, in combination, a patch applying cylinder for rolling patches progressively into contact with a material to be patched, means for driving the patch applying cylinder at a predetermined surface speed, means for positively feeding a web of patch material to

the cylinder at a lesser speed, means for severing successive patches from the patch web on the cylinder, auxiliary feeding means bearing lightly against the cylinder for cooperating with the cylinder to exert a slip drag on the leading end of the patch web before severance and to carry the patch forward without slipping after severance, and adjustable means for setting the pressure of the auxiliary feeding means against the cylinder to any value desired throughout an available pressure range of substantial extent.

14. In a patch applying machine, in combination, a patch applying cylinder for rolling patches progressively into contact with a material to be patched, means for driving the patch applying cylinder at a predetermined surface speed, means for positively feeding a web of patch material to the cylinder at a lesser speed, means for severing successive patches from the patch web on the cylinder, belt means bearing lightly against the cylinder for cooperating with the cylinder to exert a slip drag on the leading end of the patch web before severance and to carry the patch forward without slipping after severance, and adjusting means for changing the belt tension and thereby altering the pressure of the belt against the cylinder.

15. In a patch applying machine, in combination, a patch applying cylinder for rolling patches progressively into contact with a material to be patched, means for driving the patch applying cylinder at a predetermined surface speed, means for positively feeding a web of patch material to the cylinder at a lesser speed, means for severing successive patches from the patch web on the cylinder, belt means bearing lightly against the cylinder for cooperating with the cylinder to exert a slip drag on the leading end of the patch web before severance and to carry the patch forward without slipping after severance, upper and lower guide rollers supporting the opposite ends of the active or cylinder engaging stretch of the belt, and swingable arms supporting the guide rollers and arranged to increase the pressure of the rollers against the cylinder in response to increase of belt tension.

16. In a patch applying machine, in combination, a patch applying cylinder for rolling patches progressively into contact with a material to be patched, means for driving the patch applying cylinder at a predetermined surface speed, means for positively feeding a web of patch material to the cylinder at a lesser speed, means for severing successive patches from the patch web on the cylinder, belt means bearing lightly against the cylinder for cooperating with the cylinder to exert a slip drag on the leading end of the patch web before severance and to carry the patch forward without slipping after severance, upper and lower guide rollers supporting the opposite ends of the active or cylinder engaging stretch of the belt, and upper and lower pivoted arms supporting the respective rollers, said upper arm diverging slightly from the common tangent plane of the cylinder and the upper guide roller and having its pivot located slightly above said plane, and guide means for directing a lower inactive stretch of the belt means away from the lower guide roller in an upward direction and close to the pivot of the lower pivoted arm so that the lower arm will be biased lightly toward the cylinder by belt tension.

17. In a patch applying machine, in combina-

tion, a patch applying cylinder for rolling patches progressively into contact with a material to be patched, means for driving the patch applying cylinder at a predetermined surface speed, means for positively feeding a web of patch material to the cylinder at a lesser speed, means for severing successive patches from the patch web on the cylinder, a pair of belts bearing lightly against the cylinder for cooperating with the cylinder to exert a slip drag on the leading end of the patch web before severance and to carry the patch forward without slipping after severance, guide means for the respective belts, and means for individually adjusting the guide means of each belt as a unit laterally of the path of web travel.

18. In a patch applying machine, in combination, a patch applying cylinder for rolling patches progressively into contact with a material to be patched, means for driving the patch applying cylinder at a predetermined surface speed, means for positively feeding a web of patch material to the cylinder at a lesser speed, means for severing successive patches from the patch web on the cylinder, a pair of belts bearing lightly against the cylinder for cooperating with the cylinder to exert a slip drag on the leading end of the patch web before severance and to carry the patch forward without slipping after severance, guide means for the respective belts, means for individually adjusting the guide means of each belt as a unit laterally of the path of web travel, and common driving means for driving the belts in unison with the cylinder and with one another.

19. In a patch applying machine, in combination, a patch applying cylinder, means for driving the cylinder at predetermined speed, means for paying out patch web material to the cylinder at a predetermined lesser speed, rotary cutting means cooperative with the cylinder for cutting one or more patches from the web in each revolution of the cylinder as desired, loop forming means interposed between the paying out means and the cylinder to form a loop in the web between each two successive cutting operations and to yield up loop material as each cutting operation is performed, and cam means controlling the operation of the loop forming means comprising a cam shaft, a plurality of cams of like contour thereon, an actuating member operable by the cams, and means for securing the cams in different positions of relative adjustment to cause the actuating member to be operated one or more times in each revolution of the cylinder as required.

20. In a patch applying machine, in combination, a patch applying cylinder, means for driving the cylinder at predetermined speed, means for paying out patch web material to the cylinder at a predetermined lesser speed, rotary cutting means cooperative with the cylinder for cutting one or more patches from the web in each revolution of the cylinder as desired, loop forming means interposed between the paying out means and the cylinder to form a loop in the web between each two successive cutting operations and to yield up loop material as each cutting operation is performed, and cam means controlling the operation of the loop forming means comprising a cam shaft, a plurality of cams of like contour thereon, an actuating member operable by the cams, and means for fixing the cams in different predetermined angular relations to one another to cause the actuating mem-

ber to be operated one or more times in each revolution of the cylinder as required.

21. In a patch applying machine, in combination, a patch applying cylinder, means for driving the cylinder at predetermined speed, means for paying out patch web material to the cylinder at a predetermined lesser speed, rotary cutting means cooperative with the cylinder for cutting one or more patches from the web in each revolution of the cylinder as desired, loop forming means interposed between the paying out means and the cylinder to form a loop in the web between each two successive cutting operations and to yield up loop material as each cutting operation is performed, and adjustable means for controlling the operation of the loop forming means and varying the number of loop forming operations per revolution of the cylinder to cause the loop forming means to be operated once for each cutting operation and in timed relation thereto.

22. In a patch applying machine, in combination, a patch applying cylinder, a rotary cutter cooperative therewith and adapted to be equipped with one or more cutting knives, said rotary cutter having an effective diameter which is an aliquot part of the diameter of the cylinder, said cylinder including grooves for receiving anvil bars to cooperate with the rotary cutter, or for receiving non-cutting bars as required, and bar clamping means including means operable to facilitate the rapid replacement of the anvil bars by the non-cutting bars and vice versa.

23. In a patch applying machine, in combination, a patch applying cylinder, a rotary cutter cooperative therewith and having an effective diameter which is an aliquot part of the diameter of the cylinder, and means for removably securing cutting knives in selected positions on said rotary cutter, said cylinder being formed with a longitudinal groove in the periphery thereof to permit a knife to pass without cutting in a region of the cylinder which would otherwise be engaged by the knife but upon which no cutting is ever required.

24. In a patch applying machine, in combination, a patch applying cylinder, a rotary cutter cooperative with the cylinder, whose effective diameter is an aliquot part of the diameter of the cylinder, and means for removably securing cutting knives in selected positions on said rotary cutter, said cylinder including anvil bar holding recesses, an anvil bar in at least one of said recesses and one or more non-cutting bars in the remainder thereof, and said cylinder being formed with longitudinal grooves in the periphery thereof to permit knives to pass without cutting in regions of the cylinder which would otherwise be engaged by the knives but upon which no cutting is ever required.

25. In a patch applying machine, a patch cutting and applying cylinder comprising a cylinder body, a plurality of anvil bars secured to said body, and a plurality of laminated traction segments secured to the body by the anvil bars, each segment comprising a base layer of metal and a surface layer of rubber vulcanized thereto.

26. In a patch applying machine, a patch cutting and applying cylinder comprising a cylinder body, laminated traction segments each comprising a base layer of metal and a surface layer of rubber vulcanized thereto, anvil bars interposed between the edges of adjacent segments and formed with flanges to overlie the adjacent mar-

ginal portions thereof, and means for clamping the anvil bars to the cylinder body.

27. In a patch applying machine, in combination, a patch cutting and applying cylinder, a rotary cutter cooperative therewith, means for removably securing cutting knives in selected positions on said rotary cutter, said cylinder including a cylinder body, laminated traction segments each comprising a base layer of metal and a surface layer of rubber vulcanized thereto, and bars interposed between the edges of adjacent segments and formed with flanges to overlie adjacent marginal portions of the segments, a portion at least of said bars being cooperative with the knives to effect cutting, at least one of said segments being formed with a longitudinal groove in the periphery thereof to permit a knife to pass without cutting in a region of the cylinder which would otherwise be engaged by the knife but upon which no cutting is ever required.

28. In a patch applying machine comprising a patch applying cylinder, in combination, a cylinder body, curved traction segments on the surface thereof, clamping bars interposed between adjacent segments and having overhanging shoulders to overlie straight marginal portions of the segments, and means for securing the segments and the bars in place on the cylinder body comprising a disc-like member, means removably securing the disc-like member to the cylinder body, said disc-like member having notches in the periphery thereof and being formed with arcuate flanges between said notches to overlie curved marginal portions of the respective segments, clamping blocks inserted in said notches and having shoulders arranged to overlie end portions of the respective clamping bars, and means for removably securing the clamping blocks to the disc-like member.

29. In a patch applying machine, in combination, a patch cutting and applying cylinder, and a rotary cutter cooperative therewith, said cutter including a cylinder having a longitudinal groove in the periphery thereof, a plurality of angle blocks set in the groove, each including a base portion disposed in the base portion of the groove, a body portion extending upwardly therefrom and an adjusting screw threaded through said body portion, a cutter blade set in the angles of said blocks, and clamping screws threaded through the cylinder and clamping the blade and blocks in place.

30. In a patch applying machine, in combination, a patch applying and cutting cylinder, a rotary cutter cooperative therewith to cut successive patches from a web of patch material, means for driving the cylinder, means for paying out a web of patch material to the cylinder at a lesser speed than the surface speed of the cylinder, and means bearing lightly against the cylinder before the point of severance for maintaining the leading end of the web constantly in frictional contact with the cylinder.

31. In a patch applying machine, in combination, a patch applying and cutting cylinder, a rotary cutter cooperative therewith to cut successive patches from a web of patch material, means for driving the cylinder and the cutter at the same surface speed, means for paying out a web of patch material to the cylinder at a lesser speed than the surface speed of the cylinder, means for causing the cylinder frictionally to engage and draw forward the leading end of the web which extends beyond the point of cutting and to carry the cut patch forward without slipping.

after it is cut, and means bearing lightly against the cylinder in position to engage the web before it reaches the cutting point for constantly maintaining the web in frictional contact with the cylinder.

32. In a patch applying machine, in combination, a patch applying and cutting cylinder, a rotary cutter cooperative therewith to cut successive patches from a web of patch material, means for driving the cylinder and the cutter at the same surface speed, means for paying out a web of patch material to the cylinder at a lesser speed than the surface speed of the cylinder, means for causing the cylinder frictionally to engage and draw forward the leading end of the web which extends beyond the point of cutting and to carry the cut patch forward without slipping after it is cut, and idler roller means bearing lightly against the cylinder in position to engage the web before it reaches the cutting point for constantly maintaining the web in frictional contact with the cylinder.

33. In a patch applying machine, in combination, means for feeding a first material to be patched, a patch applier for rolling patches progressively into contact with the first material, means for driving the patch applier in unison with the first material feeding means, means for supplying a web of patch material to the patch applier at a slower speed than the surface speed of the patch applier, roller means for holding the web of patch material in light frictional contact with said patch applier at all times, means coacting with said patch applier for cutting patches of predetermined length from the leading end of the patch web, and means for holding the leading end of the patch web in slipping contact with the said patch applier before severing, said means after severing being adapted to carry the patch forward without slipping for application to the first material.

34. In a machine of the class described, a ro-

tating cylinder comprising a body formed with longitudinally extending grooves, longitudinal anvil bars removably secured in the grooves, a rotary cutter coacting with said cylinder and provided with projecting longitudinal knife edges which are adapted to contact said anvil bars, means for driving said cutter and cylinder at the same surface speed, and rigid cylinder segments having work engaging surfaces of suitable friction material removably attached to said cylinder body and extending between said anvil bars.

35. In a patch applying machine, in combination, means for feeding a first material to be patched, a patch cutting and applying cylinder for rolling patches progressively into contact with the first material, means for driving the patch cutting and applying cylinder in unison with the first material feeding means, means for supplying a web of patch material to the patch cutting and applying cylinder at a slower speed than the surface speed of said cylinder, and a rotary transverse cutter cooperative with the patch cutting and applying cylinder, said cylinder including an arcuate traction segment whose surface is divided longitudinally by a multiplicity of circumferentially extending grooves for facilitating release of a patch to the first material, and an unbroken longitudinally extending anvil portion adjacent the trailing boundary of said segment for cooperating with the rotary cutter.

36. In a patch applying machine, in combination, a patch cutting and applying cylinder, and a rotary transverse cutter cooperative therewith, said cylinder including an arcuate traction segment whose surface is divided longitudinally by a multiplicity of circumferentially extending grooves for facilitating patch release, and an unbroken longitudinally extending anvil portion adjacent the trailing boundary of said segment for cooperating with the rotary cutter.

EDWIN G. STAUME.
